UNITED STATES PATENT OFFICE.

FRANK J. KAUFMANN, OF TRIBES HILL, NEW YORK, ASSIGNOR TO FOWNES BROTHERS & CO., OF LONDON, ENGLAND, A COPARTNERSHIP CONSISTING OF WILLIAM GARDNER RIGDEN, HENRY URWICK, W. FOWNES RIGDEN, E. FOWNES RIGDEN, S. FOWNES RIGDEN, AND LESLIE ALAN SPAILL.

POWDER-DISTRIBUTER.

1,333,079.

Specification of Letters Patent.

Patented Mar. 9, 1920.

Application filed October 9, 1918. Serial No. 257,498.

To all whom it may concern:

Be it known that I, FRANK J. KAUFMANN, a citizen of the United States, residing at Tribes Hill, county of Montgomery, and 5 State of New York, have invented certain new and useful Improvements in Powder-Distributers, of which the following is a specification.

Reference may be had to the accompanying drawings, and the reference characters marked thereon, which form a part of this specification. Similar characters refer to similar parts in the several figures therein.

The invention relates to powder distributors whereby the powder is ejected through a nozzle by the use of a blast of air or other fluid.

The preferred form of device shown in the drawings is adapted for distributing 20 powder from a container over the surface of a web of paper, textile or knitted fabric or similar sheet material.

The principal objects of the invention are to secure a substantially uniform deposit 25 of the powder upon all parts of the surface to which it is applied; and to prevent clogging of the sifter-plate through which the powder is delivered to the blast of fluid whereby it is blown from the nozzle of the 30 distributor.

Other objects will appear in connection with the following description.

Figure 1 of the drawings is a view in side elevation showing my improved powder-distributer in its application to a machine for coating the surface of a web of paper, cloth or similar sheet material with comminuted or powdered material.

Fig. 2 is a horizontal cross-section of the 40 powder-distributer taken on the broken line 2—2, Fig. 3, viewed from above.

Fig. 3 is a central vertical section of the same taken on the broken line 3—3 in Fig. 2.

Fig. 4 is a top plan view of the sifter- 45 plate detached.

Fig. 5 is a top view of the brush for sweeping the powder across the upper side of the sifter-plate.

Fig. 6 is a cross-section of the lower portion of the device taken on the broken line 5—6 in Fig. 2.

Referring to the drawings wherein the invention is shown in preferred form, 1 is

a powder-container, preferably made of downwardly tapered form and mounted 55 upon a base, 2, containing an air-chamber, 3.

The container is preferably removably mounted upon the base by means of screws, 4, connecting together flanges, 5 on the container, and 6 on the base. 60

A perforated sifter-plate, 7, is removably mounted upon a seat, 8, on the base and forms a bottom for the container, 1.

An air-supply pipe, 9, in fixed relation to the base, 2, communicates at one side of the 65 base with the chamber, 3, extending therefrom downwardly and transversely beneath the chamber, 3, to the axial line of the base of the container, and then downwardly along said axial line forming a bearing-spindle, 10, rotatively mounted in the lower arm, 11, of a bracket, 12, whereby the distributor is mounted upon a machine in connection with which it is to be used. 70

This supply-pipe, 9, contains an air-passageway which extends down through the bearing-spindle, 10. 75

The bearing-spindle, 10, is connected with an air-supply pipe, 13, by means of a coupling, 14, which permits the bearing-spindle, 10, to be rotatively moved relatively to the supply-pipe, 13. 80

Air or other desired fluid can be supplied to the air-supply pipe, 13, under such pressure as may be desired, and the same will be 85 transmitted through the pipe, 9, to the chamber, 3.

A delivery nozzle, 15, projects from the chamber, 3, on the side opposite that with which the air-supply pipe, 9, connects. 90

In the preferred form of my invention the sifter-plate, 7, is held in substantially fixed relation to the base, 2, with respect to rotative movement by means of a pin, 16, on the base which engages a notch, 17, in the edge 95 of the plate.

A vertical spindle, 18, is arranged axially within the container, 1, having at its lower end a bearing in the sifter-plate, 7, the upper end of the spindle projecting upwardly 100 through the top of the container, and being fixedly secured by means of a screw, 19, in the upper arm, 20, of the bracket, 12.

A brush comprising a hub, 21, and a plurality of blades or vanes, 22, is slidably 105 mounted upon the lower end of the spindle,

18, just above the sifter-plate, 7, said brush having a pin-and-slot engagement at 23, with the spindle, whereby a limited vertical movement of the brush is permitted while 5 rotative movement of the brush with respect to the spindle, 18, is prevented.

A coil-spring, 24, inclosing the spindle, 18, tends to yieldingly force the brush down upon the upper surface of the sifter-plate, 7.

10 A relative rotative movement between the brush and sifter-plate, 7, may be produced in any known manner, and will serve to sweep the deposit of powder across the upper surface of the sifter-plate, preventing 15 the powder from clogging the space above the sifter-plate, and causing the powder to be delivered through the sifter-plate with substantial uniformity as to the quantity and the form as delivered to the chamber, 3.

20 In the preferred form shown, the brush is prevented from rotation by a pin-and-slot connection, 23, with the spindle, 18, while the sifter-plate, 7, is relatively moved in connection with the base, 2, and the container, 1, as well as the air-supply pipe, 9, and the nozzle, 15; and such rotative movement may be imparted in any known manner.

As a means for imparting such rotative movement, I have shown a link, 25, pivotally connected with an ear, 26, projecting from the side of the container, 1, which link may be connected with any suitable moving part of the machine in connection with which 35 the distributor is employed, whereby the container and parts connected to be relatively moved therewith will be reciprocately moved through a partial rotation, causing the nozzle, 15, to reciprocate through an arc 40 of such length as may be desired.

As illustrating one use of my improved powder-distributor, I have shown in the drawings the distributor in its relation to a machine for applying comminuted or powdered material to the surface of a web of paper, fabric or similar sheet material, the web, 27, being fed from a roll, 29, to a roll, 30, with a stretch of the web between said rolls exposed to the action of the powder-distributor.

The web may be treated in any known manner to cause the particles of powder or comminuted material to adhere thereto.

The oscillating movement of the nozzle, 55 15, of my powder-distributor causes the powder to be distributed throughout the width of the web.

The operation of my powder-distributor is as follows:

60 A supply of powder having been introduced into the container through the cap-covered top-opening, 33, as the container and parts connected to relatively move therewith are reciprocated, the powder in 65 the lower end of the container is brushed

over the upper surface of the sifter-plate, 7, by means of the vanes, 22, causing the powder to descend in small quantities through the apertures in the sifter-plate into the chamber, 3, while at the same time a blast of 70 air or other fluid under-pressure is forced into said chamber through the air-supply pipe, 9, causing the powder to be forcibly blown out from the chamber, 3, through the nozzle, 15.

The powder thus forcibly delivered from the nozzle, 15, is distributed upon the surface of the web, 27.

To more uniformly distribute the powder transversely of the web and to prevent too 80 great a deposit of powder upon the middle portion of the web, I have provided for lost-motion in the reciprocating rotative movement of the container, 1, and nozzle, 15, by forming a slot, 34, in the ear, 26, for 85 the pivotal connection with the link, 25, the connecting pivot being free to slide longitudinally of said slot.

The nozzle is thus permitted to lag behind the pivotal connection with the link, 25, at 90 the beginning of the rotative movement of the nozzle, in each direction, thus providing for an additional supply of powder to the edge portions of the web.

I have shown in the drawings a preferred 95 form of air chamber, 3, having side walls which converge downwardly in cross-section to a channel or gutter, 28, substantially in line with the blast of air from the pipe, 9, to the nozzle, 15.

This form of chamber insures the immediate delivery of the powder sifted through the plate, 7, into the path of the blast of air, thus preventing any accumulation of powder in the chamber.

What I claim as new and desire to secure by Letters Patent is:

1. In a powder-distributor and in combination, a powder-container; a sifter-plate extending across the lower end of the powder-container; an air-chamber beneath said sifter-plate; means for supplying fluid under-pressure to said air-chamber; a nozzle extending from said air-chamber; a brush adjacent to the upper side of said sifter-plate; and means for causing a relative rotative movement between said brush and said sifter-plate.

2. In a powder-distributor and in combination, a powder-container having a chambered base; a removable sifter-plate extending across the lower end of said container above said chamber, the upper side of said sifter-plate being substantially plane and being provided with numerous small 115 perforate openings; means for supplying fluid under-pressure to said chamber; a nozzle extending from said chamber; a brush adjacent to the upper side of said sifter plate; and means for causing relative rota- 120 125 130 135 140 145 150 155 160 165 170 175 180

tive movement between said brush and said sifter-plate.

3. In a powder-distributer and in combination, a powder-container having a chambered base; a removable sifter-plate extending across the lower end of said container above said chamber; means for supplying fluid under-pressure to said chamber; a nozzle extending from said chamber; a brush adjacent to the upper side of said sifter-plate; a spring for yieldingly holding said brush against the sifter-plate; and means for causing relative rotative movement between said brush and said sifter-plate.
- 10 4. In a powder-distributer and in combination, a powder-container having a chambered base, said container and base being rotatively mounted upon a vertical axis extending longitudinally of the container; an air-supply pipe and a nozzle both mounted upon said base to rotate therewith; a sifter-plate extending across the lower end of said container above said chamber rotatory with said base and container; a brush adjacent to the upper side of said sifter-plate; and means for imparting rotative movement to said base and container.
- 15 5. In a powder-distributer and in combination, a powder-container having a chambered base; means for rotatively supporting the upper end of the container; an air-supply pipe connecting with said chamber in fixed relation to said base, and having a portion extending downwardly therefrom along the axial line of the container; a support on which said downward extension of the air-supply pipe has a rotatory bearing; a sifter-plate extending across the lower end of the container above said chamber; a brush adjacent to the upper side of said sifter-plate; and means whereby rotative movement of said container and base causes a relative rotative movement between said brush and said sifter-plate.
- 20 6. In a powder-distributer and in combination, a rotatively mounted powder-container having a chambered base; means for supplying fluid under-pressure to said chamber; a nozzle extending from said
- chamber rotatory with said container and base; a sifter-plate extending across the lower end of said container above said chamber; a brush adjacent to the upper side of said sifter-plate; means whereby rotative movement of said container and base causes a relative rotative movement between said sifter-plate and said brush; a reciprocatory container-rotating member; and a slotted connection between said member and said container providing lost-motion at the beginning of the rotative movement of the container in each direction.
- 25 7. In a powder-distributer and in combination, a powder-container having a chambered base; a removable sifter-plate extending across the lower end of said container above said chamber in fixed relation to said base; a support; a spindle in fixed relation to said support extending downwardly through the upper end of the container forming a rotatory bearing therefor and having its lower end rotatively mounted upon said sifter-plate; a brush carried by said spindle adjacent to the upper side of said sifter-plate; a spring carried by said spindle tending to hold said brush against said sifter-plate; an air-supply pipe communicating with said chamber and whereby said base is rotatively mounted upon said support on an axis in line with said support; a nozzle extending from said chamber; and means for imparting a reciprocatory rotative movement to said container.
- 30 8. In a powder-distributer and in combination, a powder-container having a chambered base, the walls of said chamber converging downwardly in cross-section to a channel or gutter extending longitudinally of the distributer; means for feeding powder from said container in limited quantities to said chamber; a fluid supply-pipe leading to said chamber at one end of said channel or gutter; and a nozzle leading from said chamber at the other end of said channel or gutter.

In testimony whereof I have hereunto set my hand this 23rd day of September, 1918.

FRANK J. KAUFMANN.
